United States Patent Office.

ISAAC PEDRICK, OF BRIDGETON, NEW JERSEY

Letters Patent No. 64,901, dated May 21, 1867.

IMPROVED BEDSTEAD.

The Schedule referred to in these Letters Patent and making part of the same.

TO ALL WHOM IT MAY CONCERN:

Be it known that I, ISAAC PEDRICK, of Bridgeton, in the county of Cumberland, and State of New Jersey, have invented a new and improved Bedstead; and I do hereby declare that the following is a full, clear, and exact description thereof, which will enable others skilled in the art to make and use the same, reference being had to the accompanying drawings, forming part of this specification, in which—

Figure 1 is a vertical longitudinal section of my improved bedstead taken through the line *x x*, fig. 2.

Figure 2 is a vertical cross-section of the same taken through the line *y y*, fig. 1.

Figure 3 is a detail top view of a portion of the same, partly in section through the line *w w*, fig. 1.

Figure 4 is a detail sectional view of the same taken through the line *z z*, fig. 3.

Similar letters of reference indicate like parts.

My invention has for its object to furnish an improved bedstead, so constructed and arranged that the weight upon the bed-bottom may press against the shoulders or ends of the side and end rails, so that the posts may be detached without taking the bed-bottom apart, and that the slats may be easily turned over for dusting. And it consists in the frame for supporting the slats, in combination with the posts of the bedstead, in the combination of the post-sockets with the side and end rails with the posts and with the supporting frame, and in stringing the slats upon, or connecting them with, a cord or tape, so that they may be easily turned over for dusting without getting them out of their proper relative positions, the whole being constructed and arranged in the manner hereinafter more fully described.

A are the side rails, and B are the end rails of the bedstead, the ends of which rest against the sockets C of the posts D. The sockets C may be round, as shown in the drawings, or they may be square or octagonal, as may be desired, and they should have flanges or projections formed upon them to keep the rails in their proper position. The posts D may be passed up through the sockets C, or they may be made in two pieces and screwed into the said sockets, or the lower parts may screw into the upper parts. This latter construction would allow the upper parts of said posts to be permanently connected with head and foot-boards. E and F are the side-bars, and G and H are the end-bars of the supporting frame. These bars are connected together by double hooks, I, hooking through the ends of the said bars, and through eyes, J, formed upon or attached to the sockets C, as shown in figs. 1, 2, and 3. In case the frame E F G H is attached to an ordinary bedstead, the eyes J are attached directly to the posts. The end-bar H of the supporting frame is made in two parts, connected to each other by a swivelled or double screw, K, so that the said frame can be strained to any desired tightness. L are the slats, which are extended across the bedstead, with their ends resting upon the side-bars E and F of the supporting frame. The slats are kept in their proper relative positions by the cord or tape M, passed through slots in the ends of the slats L, and around the ends of the said slats, as shown in figs. 3 and 4, so that the slat can be turned over, when desired, for dusting or any other purpose. By this construction, by removing the posts D the bedstead is reduced to a very convenient form for moving or transportation; and by putting two of these bed-bottoms together, with the beds between them, and securing them to each other at the corners, a very convenient case is formed for carrying mirrors or other delicate articles of furniture safely.

Having thus described my invention, what I claim as new, and desire to secure by Letters Patent, is—

1. The frame E F G H K and hooks I, or their equivalent, in combination with each other and with the posts D, substantially in the manner herein shown and described, and for the purpose set forth.
2. The post sockets C, in combination with the posts D, rails A and B, and frame E F G H K, substantially as herein shown and described, and for the purpose set forth.
3. Stringing the slats L upon, or connecting them with, a cord or tape M, substantially in the manner herein shown and described, and for the purpose set forth.

The above specification of my invention signed by me this 18th day of February, 1867.

ISAAC PEDRICK.
